(57) **CLAIM**

I claim the ornamental design for a segment of a hockey puck display, as shown and described.

DESCRIPTION

FIG. 1 is a front elevational view of a segment of a hockey puck display, showing my new design;

FIG. 2 is another front elevational view thereof;

FIG. 3 is an elevated perspective view thereof; and,

FIG. 4 is another elevated perspective view thereof. The broken lines shown in FIGS. 1-4 are for illustrative purposes only and form no part of the claimed design.
